US0D1106972S

(12) **United States Design Patent** (10) **Patent No.:** **US D1,106,972 S**
(45) **Date of Patent:** **** Dec. 23, 2025**

(54) **ROOFTOP JUNCTION BOX**

(71) Applicant: **Unirac, Inc.**, Albuquerque, NM (US)

(72) Inventors: **Alex Cheng-Chi Yang**, Redwood City, CA (US); **Byron James Madden**, Kingwood, TX (US); **Ryan Mac McClister**, Houston, TX (US)

(73) Assignee: **Unirac, Inc.**, Albuquerque, NM (US)

(**) Term: **15 Years**

(21) Appl. No.: **29/923,028**

(22) Filed: **Dec. 27, 2023**

(56)

(57) **CLAIM**

The ornamental design for a rooftop junction box, as shown and described.

DESCRIPTION

The sole FIGURE is a perspective view of a rooftop junction box embodying our new design.

The dash-dash broken lines showing a portion of the rooftop junction box form no part of the claimed design. The dash-dot lines represent boundary lines and form no part of the claimed design.

1 Claim, 1 Drawing Sheet
